Primary Examiner — Richard Kearney*Assistant Examiner* — Sarah L. Smith(74) *Attorney, Agent, or Firm* — Craig R. Miles; CR MILES P.C.(57) **CLAIM**

The ornamental design for a toy, as shown and described.

DESCRIPTION

FIG. 1 is a front view of a toy, showing my new design; FIG. 2 is a rear view thereof;

FIG. 3 is a top view thereof;

FIG. 4 is a bottom view thereof;

FIG. 5 is a lateral view (right side) thereof;

FIG. 6 is a lateral view (left side) thereof; and,

FIG. 7 is a perspective view thereof.

The broken lines shown in the drawings do not form a part of the claimed design.
